Primary Examiner — Jae Liang*Assistant Examiner* — Riya Salil Kamat(74) *Attorney, Agent, or Firm* — Barnes & Thornburg LLP(57) **CLAIM**

The ornamental design for an exercise machine component as shown and described.

DESCRIPTION

FIG. 1 is a front perspective view of an exercise machine component showing our new design;

FIG. 2 is a front elevation view of the exercise machine component of FIG. 1;

FIG. 3 is a right side elevation view of the exercise machine component of FIG. 1, the left side being a mirror image thereof; and,

FIG. 4 is a bottom plan view of the exercise machine component of FIG. 1.

The broken lines shown in the drawings are for purposes of illustrating portions of the exercise machine component that form no part of the claimed design.
